UNITED STATES PATENT OFFICE.

CHARLES C. MORGAN, OF BROOKLYN, ASSIGNOR TO UNION PAPER-COLLAR COMPANY, OF NEW YORK, N. Y.

DESIGN FOR A STAMP.

Specification forming part of Design No. 6,025, dated August 13, 1872.

Specification describing a Design for a Stamp, produced or invented by CHARLES C. MORGAN, of Brooklyn, county of Kings, State of New York.

Design for a Stamp.

The figure in the accompanying drawing fully represents my design for a stamp, of which A is the body, and B a coupon attached to one side of the same. Upon the upper end of the body of the stamp are curved ribbons or scrolls, on which are marked the words "License Stamp of Union Paper Collar Co.," or equivalent words indicating the character and object of the stamp; and between these scrolls are two clasped hands and a circle of stars, indicative of union. The figures 1^a, or other figures or characters designating the class of goods for which the stamps are intended, are marked upon tablets a at each of the upper corners of the stamp, and beneath

the same, at the sides of the stamp, are vertical tablets b. The lower portion of the body of the stamp is occupied by columns of dates of patents, and above the same is a space for a signature. The coupon B has at each end the word coupon, and in the center a signature and dates of patents.

The stamp may be printed in any color or colors, and may be used with or without the coupon.

I claim—

The design for the stamp A, substantially as described and illustrated, with or without the coupon B.

In testimony whereof I have signed my name to this specification in the presence of two subscribing witnesses.

C. C. MORGAN.
